GUIDE FOR USE WITH ZIPPER

Richard E. Weston and Reva King, both of 141 Pass Ave.,
Burbank, Calif.

Filed Jan. 29, 1962, Ser. No. 68,550

Term of patent 14 years

(Cl. D17—8)

FIG. 1 is a perspective view of a guide for use with zipper showing our new design in full lines, the same being placed within a garment placket depicted in broken lines.

FIG. 2 is a top plan view;

FIG. 3 is a side view;

FIG. 4 is a forward end view;

FIG. 5 is a rearward end view; and

FIG. 6 is a bottom plan view thereof.

We claim:

The ornamental design for a guide for use with zipper, substantially as shown and described.
